UNITED STATES PATENT OFFICE.

ROBERT H. BEAUMONT, OF RADNOR, PENNSYLVANIA, ASSIGNOR TO R. H. BEAUMONT COMPANY, OF PHILADELPHIA, PENNSYLVANIA, A CORPORATION OF PENNSYLVANIA.

TAKE-UP FOR SKIP-HOIST ROPES.

Application filed February 1, 1922. Serial No. 533,213.

To all whom it may concern:

Be it known that I, ROBERT H. BEAUMONT, a citizen of the United States, residing in Radnor, Delaware County, Pennsylvania, 5 have invented certain Improvements in Take-Ups for Skip-Hoist Ropes, of which the following is a specification.

One object of my invention is to provide a simple and effective means for taking up the 10 slack in hoisting ropes, especially ropes used for operating skip hoists, in which one end of the rope is attached to the bail of a bucket.

A further object of the invention is to provide means for firmly holding the rope 15 end to the adjustable sheave.

These objects I attain in the following manner, reference being had to the accompanying drawings, in which:

Fig. 1 is an end view of a skip hoist 20 bucket to which my invention is applied;

Fig. 2 is a side view of the bucket;

Fig. 3 is an enlarged sectional view 25 through the bail of the bucket on the line 3—3, Fig. 4;

Fig. 4 is a sectional view on the line 4—4, 30 Fig. 3;

Fig. 5 is a sectional view on the line 5—5, Fig. 3; and

Fig. 6 is a side view of a tool for operating the take-up device.

Referring to the drawings, 1 is the bucket of a skip hoist having a bail 2 consisting of a cross member 3 made of two channel beams connected to links 4 at the bottom of the 35 bucket by side members 5. 6 is the hoisting rope, which is attached to a sheave 7 adjustably secured to the beams 8 of the cross member by bolts 9, which extend through holes in the beams and holes in the 40 sheave. The hub 10 of the sheave extends through openings in the beams. In the hub is a rectangular (or other shaped) opening 11 to correspond with the shape of the tool 45 12 by which it is turned. This tool is shown in Fig. 6 and has a handle 13.

The sheave has a wide rim 14 for the rope. This rim is flanged at 15. 16 is a web connecting the rim of the sheave to the hub. In the rim is an opening 17 through which 50 the rope passes. The end of the rope is coiled around the hub and is secured to the web 14 by U-shaped clamp bolts 18. On the web 16, on each side of the clamp bolts,

are ribs 19, which act with the bolts to secure the rope firmly to the sheave.

55

Four clamp bolts are shown, but it will be understood that one or more bolts may be used, depending upon the size of the bucket and its load. There are four sets of holes 20 for the passage of the locking bolts 60 9 so that, when the tool is inserted in the hole 11, the bolts 9 can be withdrawn to allow the sheave to be turned on its pivot to take up the slack of the rope, or to alter the position of the bucket. After the sheave is 65 adjusted, the bolts can be placed in position, securing the sheave to the beams.

21 are rope guards, which are secured to the beams on each side of the rope.

By the above construction, it will be seen 70 a very simple yet substantial take-up for ropes is provided, which can be easily mounted on the bail of a hoisting bucket.

I claim:

1. The combination in a rope take-up, of 75 a support; a sheave mounted in said support; means for adjustably securing the sheave to the support; an opening in the rim of the sheave; and a rope clamp for clamping the end of a rope which extends through 80 the opening in the rim of the sheave.

2. The combination in a rope take-up device, of a support; a sheave having a rim, web and a hub, said hub being mounted in 85 the support; means for adjustably securing the sheave to the support, the rim having an opening; a clamping device on the web; and a rope extending around the sheave and through the opening in the rim, the end of the rope being engaged by the clamping device.

3. The combination in a rope take-up device, of a support; a sheave having a rim, web and hub, said hub being mounted to 95 turn freely in the support; a series of holes in the sheave and support; bolts extending through said holes to secure the sheave to the support, the rim having an opening therein for the passage of a rope; and a series of clamps on the web for securing the 100 end of the rope to the sheave.

4. The combination of a bucket; a bail having a cross member consisting of two beams spaced apart; a flanged sheave located in the space, the hub of the sheave 105 having its bearings in the beams; bolts ex-

tending through the beams and through the sheave by which the sheave is adjustably secured to the beams, the rim of the sheave having an opening for the passage of the 5 rope; and a series of clamps on the sheave by which the rope is secured to the sheave.

5. The combination of a support; a sheave mounted in the support and having an opening therein to receive a tool by which it can 10 be turned; means for adjustably securing the sheave to the support, the rim of the sheave having an opening for the passage of a rope; and a series of U-shaped clamps secured to the web of the sheave and engaging 15 the rope.

6. The combination in a take-up for skip bucket hoisting ropes, of a bucket; a bail therefor having two cross beams; a flanged sheave located between the beams, the hub of the sheave extending into bearing openings in the beams; bolts extending through the beams and the sheave, the hub of the sheave being shaped to receive a turning tool, the rim of the sheave having an opening for the passage of a rope; and a series 20 of clamps on the web of the sheave, each clamp having a rib on each side for engaging the rope.

ROBERT H. BEAUMONT.
